Inventor:

Geo. Sylvestor Tiffany

UNITED STATES PATENT OFFICE.

GEORGE S. TIFFANY, OF LONDON, CANADA.

DRAIN-TILE MACHINE.

SPECIFICATION forming part of Letters Patent No. 258,614, dated May 30, 1882.

Application filed March 17, 1881. (No model.)

To all whom it may concern:

Be it known that I, GEORGE SYLVESTER TIFFANY, of London, Canada, have invented Improvements in Machines for Making Drain-

5 Tiles, of which the following is a specification.

My invention relates to that part of a drain-tile machine called the "cutting-table," and it consists in the mechanism for raising and lowering the table, whereby the table may be 10 quickly raised or lowered to adapt it to receive the tiles from the die of the machine, and in such a way that the table will always be level; and, secondly, in the means used to fasten the table at any plane of elevation to which it may 15 be raised.

Cutting-tables have heretofore been raised and lowered by means of racks and cog-wheels, which are cumbersome and expensive, and by means of hand-screws, raising one end of the 20 table and then the other, requiring considerable time, labor, and skill to raise or lower and adjust the table to a level.

In the accompanying drawings, in which similar letters of reference indicate like parts, 25 Figure 1 is a perspective of a cutting-table for a drain-tile machine embodying my invention, and Fig. 2 is an end elevation of the same.

The tile as it issues from the die passes over the rollers J, which have bearings in the frame 30 B, and to the side of the frame B a cutting-frame, A, is hinged, these parts being substantially the same as in cutting-tables in common use. Beneath the frame B is a frame, C, of the same width, and the two frames are connected by four hinges, two on each side, I I I I. Each hinge may be a plain wire bar having a 35 hole near each end. A loosely-fitting bolt passes through each hole, one into the frame C and one into the frame B. The hinges or 40 hinged supports I I I I are so attached to the frames B and C that the frames will be parallel and the hinges on the same side of the frames B C will be parallel.

It will be seen that the two frames will be 45 connected to each other on each side like the two bars of a parallel ruler, and that the frame B may be raised or lowered, turning on the

hinges I I I I, and will always be parallel to the frame C.

To support the cutting-table at any point to 50 which it may be raised, I fasten two slotted bars, H H, one on each side of the frame or cutting-table B, by loosely-fitting bolts, so that the bars may be turned freely on the bolts, and pass a bolt or binding-rod, K, through the 55 frame C and through the slots in the bars H H. On one end of the rod K is a head, and on the other end a screw-thread and a crank-nut, L. By turning the crank-nut L so as to bind the slotted bars H H against the frame C the 60 two frames B C become rigidly attached to each other.

The foundation-frame D and rockers E E E E are the same as described in a patent (numbered 156,188) of the United States granted to me, 65 and the parts may be used with the improvements described in this specification in connection with machines that mold tiles continuously; but for machines that mold intermittently—allowing time to cut off while the tiles 70 are not moving—simply a suitable foundation would be required for the frame C.

The same movement of the frame B in relation to the frame C may be effected with a greater and even a less number of hinges or 75 hinged supports I I I I, and the form may be varied. I do not therefore limit my claim to the number or the particular form of the hinge represented.

What I claim is—

1. The combination, in the cutting-table of a drain-tile machine, of the hinges or hinged supports I I I I and frame C, substantially as and for the purpose herein set forth. 80
2. The combination of the slotted bars H H, 85 binding-rod K, crank-nut L, and frame C with the cutting-table of a machine for making drain-tiles, substantially as and for the purpose herein specified.

GEO. S. TIFFANY.
